(57) **CLAIM**

The ornamental design for a portable personal computer, as shown and described.

DESCRIPTION

FIG. 1 is a perspective view of a portable personal computer in an open configuration;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof;

FIG. 8 is a perspective view thereof shown in an alternate position;

FIG. 9 is a front view thereof;

FIG. 10 is a back view thereof;

FIG. 11 is a side view thereof;

FIG. 12 is another side view thereof;

FIG. 13 is a top view thereof;

FIG. 14 is a bottom view thereof;

FIG. 15 a perspective view thereof shown in a flat position; and,

FIG. 16 is a perspective view thereof with a portion shown at an angle.

Broken lines shown in the drawings illustrate portions of the portable personal computer and form no part of the claimed design.
